ELECTRIC HEATER FOR HOT AIR OR STEAM BATHS

Everett R. Scott, 6141 Fleur Drive, Des Moines, Iowa,
and Reinhold Melvin Hanson, 333 S. Green St., Boone,
Iowa

Filed Apr. 27, 1964, Ser. No. 79,698

Term of patent 14 years

(Cl. D81—10)

Fig. 1

Fig. 2

Fig. 3

Fig. 4

FIG. 1 is a top plan view of an electric heater for hot air or steam baths, showing our new design;

FIG. 2 is a side elevational view thereof, with the opposite side elevational view thereof being identical;

FIG. 3 is a rear elevational view thereof; and

FIG. 4 is a front elevational view thereof.

We claim:

The ornamental design for an electric heater for hot air or steam baths, substantially as shown.
